UNITED STATES PATENT OFFICE.

HIRAM BARBER, JR., OF MITCHELL, DAKOTA TERRITORY.

SPRING DRAFT ATTACHMENT FOR VEHICLES.

SPECIFICATION forming part of Letters Patent No. 410,230, dated September 3, 1889.

Application filed January 29, 1887. Serial No. 225,889. (No model.)

To all whom it may concern:

Be it known that I, HIRAM BARBER, Jr., a citizen of the United States, residing at Mitchell, in the county of Davison and Territory of Dakota, have invented a certain new and useful Improvement in Spring Draft Attachments for Wagons, Sleds, and Plows, of which the following is a full, clear, concise, and exact description, reference being had to the accompanying drawings, forming a part of this specification.

My invention relates to spring draft attachments, and is designed more particularly to be used upon wagons, sleds, and plows; and its object is to provide a yielding connection between the evener or whiffletree and the pole or beam, the advantages of which, in matters of draft, are well known.

My invention consists in a coiled spring and a longitudinally-moving box or guide-case including the same, in combination with a bolt passing through the case and tongue or beam.

My invention further consists in certain details and combinations herein particularly described and claimed.

The power applied to the evener, by which the vehicle is started forward, is exerted against the rear end of the coiled spring, and the front end of the coiled spring being limited by the bolt passing through the pole the spring is compressed as the case surrounding the spring to which the evener is attached is moved forward upon the pole. The sliding or longitudinally-moving case is thus used as a draw-bar and the force with which the case is drawn forward is exerted to compress the coiled spring, slots being provided in the case through which the bolt passes.

In the accompanying drawings, which are illustrative of my invention, Figure 1 is a side elevation of my spring draft attachment applied to the pole or tongue of a wagon. Fig. 2 is a plan of the same. Fig. 3 is a vertical longitudinal central section thereof upon line $\alpha\alpha$ of Fig. 2. Fig. 4 is a view thereof as seen from sectional line yy of Fig. 3. Fig. 5 is a detailed view of the pin or core of the spring, the head of the pin being made to conform to the shape of the bolt which passes through the slots in the case and the pole. Fig. 6 is a side elevation of a modification of my spring

draft attachment. Fig. 7 is a top view of the same. Fig. 8 is a sectional view showing the same applied to the under side of the tongue. Fig. 9 is a sectional view upon line zz of Fig. 8.

I will describe my invention first as illustrated in Figs. 1, 2, 3, 4, and 5. The case a is a casting, which may be semi-cylindrical, so as to rest squarely upon the beam and at the same time conform as nearly as may be to the shape of the coiled spring. The slots b and c are provided in this guide or case a , and the bolt d passes through these slots, as shown more clearly in Fig. 3. When the coiled spring e is in its normal position expanded, the bolt comes in the front portions of the slots, as shown. The core or head-block f is placed, as shown, within the coil, its head being fitted to and resting against the fixed bolt d . A fixed stop is thus provided at the front end of the spring, while the rear end of the spring rests in its seat provided in the rear end of the guide-case, as shown. The clasp g is held securely to the beam by a bolt h , provided with nuts h' h'' . A strap i , secured to the upper portion of the clasp, extends forward and is held by the bolt d at the front. The clasp fits closely about the case, and in connection with the bolt d forms the guide or bearings for the case as it is moved longitudinally back and forth upon the pole or beam. I term the clasp g and strap i , taken together, the "hammer-strap," for it is evident that were the case removed the evener might be attached to the wagon in the ordinary way by means of this strap and the bolt d . The evener is connected with the case a by means of a clevis k , or in any other suitable manner, the case being cut away at the top, so as to admit the lugs of the clevis through which the pin l passes. The case being thus cut away above the clevis, it is evident that the evener may be raised, since the clevis may be turned upwardly upon the pin l , as described. The spring may be, say, ten inches in length, and the slots b c each, say, four and one-half inches, so as to conform in length, as nearly as may be, to the maximum amount of the compression of the spring. These proportions may be varied according to the amount of compression desired.

The operation of my spring draft attachment will be readily understood from the foregoing description. Power being applied to the eyener, the case will be moved forward upon the tongue or beam, the slots *b c* moving over the bolt *d* as the spring is compressed. It is evident that when the case has moved forward the whole length of the slots its further movement will be arrested by the bolt *d*, and thus during the time that the spring is being compressed the bolt *d* serves as a fixed stop at the front end of the spring. The power of the bolt *d* to resist the forward movement of the case is at all times aided by the hammer-strap. It is evident, however, that the hammer-strap and bolt *d* might be disconnected, or the hammer-strap may even be entirely dispensed with without rendering the device inoperative.

The modification of my device (shown in Figs. 6, 7, 8, and 9) consists, principally, in providing a rod or brace *m*, which is connected with the bolt *d* in front, and passing back through the hollow case or head-block is connected at the rear with the tongue or beam. The case *a* is in all respects the same as heretofore described, one or more clips or clasps passing over the case in connection with the slots serving to guide the case as it is moved longitudinally back and forth. The rod or brace gives to the attachment a high degree of strength. I therefore prefer to use the rod or brace rather than the strap attachment, where the draft is very heavy and accompanied with jerks—as, for example, in starting logging-sleds.

Having thus described my invention, I claim as new and desire to secure by Letters Patent—

1. In a draft attachment for vehicles, the combination, with the pole, of the tubular casing adapted to slide thereon, provided with a hook or clevis at its forward end and longitudinal slots in its top and bottom, a vertical bolt passing through the slots and the pole and provided at its upper end with a head and at its lower end with a nut, and the coiled spring interposed within the casing between its rear end and the fixed vertical bolt, whereby the spring is compressed when the

casing is moved longitudinally forward on the pole, substantially as specified.

2. In a draft attachment for vehicles, the combination, with the pole, of the tubular casing adapted to slide longitudinally thereon and provided with the longitudinal slots in its top and bottom, the headed bolt passing downward through the slots in said casing and through the pole and secured by a nut on its lower end, the spring interposed between the bolt and the closed end of the casing, and the clasp or band *g*, secured to the pole and extending over the casing as a guide for its longitudinal movement, substantially as described.

3. In a draft attachment for vehicles, the combination, with the pole, of the tubular casing provided with the slots *b c* in its top and bottom, the rigid bolt *d* in the pole projecting through the slots in the casing, the clasp or band *g*, secured to the pole and extending over and around the casing, the hammer-strap connecting the head of the bolt and the fixed band *g*, and the coiled spring within the casing between its closed end thereof and the fixed bolt, substantially as specified.

4. In a draft attachment for vehicles, the tubular casing *a*, provided with longitudinal slots in its top and bottom, the headed bolt *d*, projecting through the slots of the casing and through the pole and provided with a nut on its lower end for securing the casing to the pole, whereby it is adapted to move longitudinally back and forth thereon, the band *g*, secured to the pole and surrounding the casing as a guide to its longitudinal movement, the strap *i*, connecting the head of the bolt *d* with the band *g*, the coiled spring within the casing and bearing against its rear end, and the core *f* within the coil, having its head resting against the fixed bolt *d*, all combined and arranged substantially as and for the purpose described.

In witness whereof I hereunto subscribe my name this 27th day of January, A. D. 1887.

HIRAM BARBER, JR.
